UNITED STATES PATENT OFFICE

REES BEYNON, OF CHICAGO, ILLINOIS, ASSIGNOR TO DRYDEN RUBBER COMPANY, OF CHICAGO, ILLINOIS, A CORPORATION OF ILLINOIS

BUFFER

Application filed June 13, 1929. Serial No. 370,645.

This invention relates in general to buffers which may be used on various types of doors, but are particularly adaptable for cushioning the closing impact of automobile doors and preventing them from rattling, when in the closed position.

The usual practice in the manufacture of automobiles is to provide the doors with buffers, which may be either of the adjustable or non-adjustable type. The common form of adjustable buffer has a slotted buffer block which is secured to the door jamb by means of a screw extending thru the slot. In order to compensate for wear, the screw is loosened, the buffer block shifted and the screw tightened to secure the block in place. The disadvantage of this arrangement is that the screw engages a wooden door jamb and after frequent loosening and tightening the threads in the screw hole become worn and the screw cannot be tightened. In the non-adjustable type wear is not compensated for, but instead a new buffer block is installed, when necessary.

The object of this invention is to provide a buffer in which the wear will be compensated for automatically.

It is also an object of this invention to provide a buffer having a buffer block which may, when desirable, be easily changed without the loosening of any screws.

Other and further important objects of this invention will be apparent from the disclosures in the specification and the accompanying drawings.

This invention, in a preferred form, is illustrated in the drawings and hereinafter more fully described.

On the drawings:

Figure 1 is an elevation view of a door jamb equipped with a buffer embodying this invention.

Figure 2 is the same as Figure 1, except that the cover plate of the container is removed.

Figure 3 is a transverse sectional view thru the container, cover plate and buffer block spring.

Figure 4 is a sectional view showing the buffer mounted on a door jamb and the rel-

ative relation of the door in the closed position.

Figure 5 is a modification of Figure 4, showing a sectional view of the buffer mounted on a door jamb.

As shown on the drawings:

In the application of this invention to automobile doors, it is preferred to mount the buffer in a door jamb 1, which is rabbeted at 2 to receive the striking portion of the door when closed. A socket 3 is made in the face 4 of the door jamb for receiving the metal container 5 shown in section in Figure 4. This socket is made, when the door jamb is of wood, by drilling a round shallow hole of the required depth. This hole is then opened to the rabbeted edge between horizontal lines that are tangential to the circular hole.

The container 5 is preferably constructed of sheet metal and is rectangular in cross section as shown in Figure 3, having a bottom 6 and vertical sides 7 which terminate at their upper edge into outwardly turned flanges 8. An end 9 of the container is circular in form and is integral with the sides 7 which are tangential to the circular end. The opposite end of the container is open for the insertion of a buffer block 10. At the open end, the sides 7 have inturned flanges 11 which engage outwardly turned flanges 12 of the buffer block and limit the outward movement of the block relative to the container. An aperture 13a is positioned at the center of the circular portion of the container bottom, thru which a screw 13 may be inserted for holding the container in the socket. A cover plate 14 extends outwardly over the vertical walls of the container and has inwardly rolled flanges 15 which slidably engage the outwardly turned flanges 8 of the walls 7. Opposed depressions 16 are made in the cover plate, with a space between their adjacent ends for engaging the top edge of the circular end 9 to prevent the cover from being jarred loose by car vibrations. A flat spring is formed into a circle leaving a space between its ends. The spring 17 fits into the container as shown in Figure 2, the portion opposite the free ends pushing against the

buffer block and moving it outwardly until the flanges 12 are against the flanges 11.

A modified form of mounting is shown in Figure 5. The container does not have a cover as shown in the preferred form of mounting. The container 19, Figure 5, is cup-shaped, having inturned flanges 20 on its bottom face for retaining the buffer-block spring 21 in place. The spring 21 is the same as the spring 17, Figure 4. The top face of the container has an aperture for receiving the mounting screw 22 which extends thru the face into the door jamb 23 and holds the buffer in place in the socket 24 which is similar in all respects to the socket 3 in Figure 4. The buffer block 25 is the same as in the preferred form, having outwardly turned flanges for engagement with inwardly turned flanges on the end face of the container.

In the use of this invention, the container is positioned in the socket and secured by the screw 13 to the door jamb; the buffer block is inserted in the open end of the container and the spring placed back of it. The cover plate is then slipped over the front face flanges of the container and secured by the depressed portions of the cover engaging on each side of the circular end wall of the container. The buffer as thus mounted, will project into the rabbeted portion of the door jamb. It is, therefore, obvious that when the door 18 is closed it will compress the buffer block, which is made of a resilient material. As the door continues to its fully closed position, the increased pressure against the buffer block will cause it to move inwardly against the pressure of the spring 17.

The use of this invention, therefore, provides a buffer which automatically compensates for the wear of the buffer block which, when desired, may easily be replaced by a new one by simply sliding back the cover plate, thus permitting the removal of the old block and the insertion of a new one; without having to loosen any screws.

I am aware that many changes may be made, and numerous details of construction may be varied through a wide range without departing from the principles of this invention, and I, therefore, do not purpose limiting the patent granted hereon, otherwise than necessitated by the prior art.

I claim as my invention:

1. A buffer, comprising a metal container open on its front face and at one end to receive a buffer block, and having outwardly turned flanges in the plane of said front face, a face plate projecting beyond the walls of said container and having inturned edges for engagement with said outwardly turned flanges of the container, a buffer block disposed in said container, and means tending to prevent movement of said buffer block relative to said container.

2. A door buffer, comprising a metal container open at its front face and at one end to receive a buffer block and having outwardly turned flanges in the plane of said front face, a cover plate slidably engaging said flanges, and a buffer block disposed in said container.

In testimony whereof I have hereunto subscribed my name at Chicago, Cook County, Illinois.

REES BEYNON.
